UNITED STATES PATENT OFFICE.

WERNER HEYN, OF HAMBURG, GERMANY.

SELF-ACTING SIPHON.

Application filed June 7, 1927, Serial No. 197,216, and in Germany August 2, 1926.

This invention relates to apparatus of the kind in which an overflow of water through a tube or conduit is utilized to set up siphon action in said tube by carrying bubbles of air from the tube through the tail-water and discharging same into the atmosphere. In such apparatus as heretofore constructed, such discharge has taken place over the lower edge of the siphon tube, so that in some instances, as the level of the tail water rises, the air bubbles which are projected thereinto by the overfall jet have to traverse an almost vertical path of about 3 meters under water before reaching said lower edge. Hence the exhausting of the air takes a considerable time and the setting up of the siphon action is correspondingly delayed.

The object of the present invention is to provide means for reducing to the minimum possible, the underwater journey of the air bubbles and this, quite irrespective of the level of the tail water.

The invention is hereinafter described with reference to the accompanying drawings, in which:

Figure 1 is a central vertical section of one form of improved siphon according to the invention;

Figure 2 is a sectional view taken on the line *a*—*b* of Figure 1;

Figure 3 is a view, similar to Figure 1, of a different constructional form of siphon;

Figure 4 is a sectional view on an enlarged scale of one of the outlet ledges of Figure 3 and

Figure 5 is a sectional view taken on the line *c*—*d* of Figure 4.

The means according to this invention consists in the employment of several submerged outlet ledges or recesses *T* or *T'*, arranged above and adjacent to each other, the several ledges or recesses either running round the inner wall of the outfall leg of the siphon in a horizontal plane as shown at *T* in Figures 1 and 2 or arranged as illustrated in Figure 3, that is to say, parallel with the back wall and on the inner side of the outer wall of the outfall leg. The ledges *T'* running parallel with the back wall are arranged

50 at a short distance from the said wall, ex-

tending across the leg between and supported by the two side walls, pipes *L* therefrom being led through the side walls or the outer wall, while the ledges *T* in the outer wall are of similar construction to those illustrated 55 in Figures 1 and 2.

Each of these outlet ledges, when submerged by the rise of the tail water in the siphon, constitutes a partition wall between the siphon chamber and the outer air, so that 60 the overfall jet can expel the air bubbles from the siphon chamber, through several of the outlet ledges simultaneously. The air from the bubbles collecting at each individual ledge reaches the outer air by a separate 65 pipe *L*.

Each of the pipes *L* terminates either in a flap-valve, with a vertically depending flap *L'*, as shown in Figures 1 and 2, or, after passing over the summit of the siphon, ends 70 in a chamber *A*, shut off from the external atmosphere and into which a pipe *R*, open at both ends, enters as far as the level of the head water in the said chamber *A*, see Figure 3. Both the pipes *R* and the overfall 75 crests can be adjustably constructed, and are therefore capable of being adapted to different head water levels, for example, summer and winter levels.

To reinforce the suction at the start of the 80 action of the siphon, one or two side siphons are provided in the lateral walls of the main siphon, with their horizontal overflow edge running at right angles to the crest of the main overfall at an elevation corresponding 85 to that of the main overflow crest, and there are collecting channels *S* behind the horizontal overflow edge of the side siphon or siphons, which collect the overfall water and discharge it into the tail waters. When the 90 head water level rises above the overflow point inside the siphon chamber the water at first flows in a thin layer over the crest of the main overfall and over the horizontal overflow edge of the auxiliary side siphon or 95 siphons which corresponds in height to the overflow crest of the main siphon. The water thus flowing into the channel *S* of the side siphon or siphons collects in the channel and forms a strong jet which by virtue of the 100

slight inclination of the bottom of the channel is directed against the submerged ledges reinforcing the suction at the start of the overflow.

5 The method of operation of a siphon working with a pipe L terminating in a chamber A (Figure 3) will also now be particularly described.

Supposing that the level of the head-water 10 has risen by 1 cm., a water jet, materially reinforced from the collecting channels S, flows over the weir top, through the grating G and between the back of the siphon and the wedge K, into the tail water. Whatever 15 may be the level of the tail water, however, at this moment, or later, when suction has begun in the siphon pipe, the air bubbles carried along in the water, immediately collect under the water-covered outlet ledges, 20 thus giving rise to a slight overpressure within the pipes L communicating with them, and practical experience shows that this overpressure is sufficient to force the water in the corresponding chambers A, which has 25 also risen by 1 cm., down again to the height of the overflow point, so that the air bubbles can escape into the atmosphere, by the proper pipes R.

It is to be understood that each pipe L terminates in a separate chamber A which has 30 its appropriate pipe R. The pipes L of those outlet ledges which are not submerged in the tail water, are open to the siphon chamber and closed to atmosphere by the water seal 35 in the respective chambers A. Hence, once the siphon action has been started by the escape of water-borne air from the siphon chamber as above described, the air in the pipes of the unsubmerged ledges is rarefied 40 to the same extent as that in the siphon chamber. Thus, in the neighborhood of the siphon inlet there will be, at the commencement of the siphon action, three different water levels, namely, the head water level, the 45 slightly lower level in the chamber or chambers A appertaining to the submerged ledge or ledges, and the slightly higher level in those chambers A appertaining to the unsubmerged ledges, produced by the rarefaction 50 just referred to. As this low pressure subsists in these chambers A and pipes L at the moment when the respective ledges T or T' in turn become submerged by the rise of the tail water, the passage of the air there- 55 into is facilitated, overpressure being thereafter produced which forces down the level of the water in the chamber A sufficiently to allow the compressed air to escape through the pipes R. In this way, the siphonic action 60 is progressive, being augmented as the flow increases, and the siphon will carry away a greater or less volume of water, depending on the volume flowing to it each second from the head race.

65 In order to accelerate the suction, use can

be made of the wedge K, to split up an overfall jet that is thicker than about 0.16 meter, and to divert it to the neighbourhood of the outlet ledges in the siphon wall W (Figure 3).

When the flow of water to the siphon ceases and the level of the head water falls to the level of the overflow point, air is admitted to the siphon tube through the pipe R, chamber A, pipe L and outlet ledge T or T', the siphon action being thus gradually checked. In many cases, however, an arrangement such as that illustrated in Figure 1, will be found indispensable.

Having described my invention, I declare 80 that what I claim and desire to secure by Letters Patent is:—

1. In a self-acting siphon such as described, a plurality of outlet ledges in the lower part arranged one above, and adjacent to, another 85 adapted to be submerged by the tail water at various levels of same and to discharge simultaneously through pipes communicating with a plurality of said outlet ledges, air carried into the tail water by the overfall jet. 90

2. In a self-acting siphon such as described, a plurality of outlet ledges in the lower part arranged one above, and adjacent to, another, an air passage adapted to connect each of said outlets with the atmosphere, a water sealed chamber through which said connection to atmosphere is effected, and means determining the sealing and unsealing of said chamber according to the level of the head water. 95

3. In a self-acting siphon such as described, a plurality of outlet ledges in the lower part arranged one above, and adjacent to, another adapted to be submerged by the tail water and to discharge from a plurality 100 of said outlets simultaneously air carried into the tail water by the overfall jet, and a wedge-shaped breakwater in the path of the overfall jet adapted to divert said jet towards a plurality of the outlet ledges. 110

4. In a self-acting siphon such as described, a plurality of outlet ledges in the lower part arranged one above, and adjacent to, another adapted to be submerged by the tail water and to discharge from a plurality 115 of said outlets simultaneously air carried into the tail water by the overfall jet, at least one auxiliary side siphon within the main siphon, and collecting channels adapted to augment the overfall jet and guide it towards the outlet ledges. 120

In testimony whereof, I have affixed my signature hereto.
